UNITED STATES PATENT OFFICE

JOHN COOK, OF MUNCIE, INDIANA

DESIGN FOR A SMOKER'S STAND

Application filed August 22, 1929. Serial No. 32,511. Term of patent 7 years.

To all whom it may concern:

Be it known that I, JOHN COOK, a subject of Great Britain, residing at Muncie, in the county of Delaware and State of Indiana, have invented a new, original, and ornamental Design for a Smoker's Stand, of which the following is a specification, reference being had to the accompanying drawings, forming part hereof.

I claim:

The ornamental design for a smoker's stand as shown.

JOHN COOK.
